BEADED TOY TRAIN

Robert Y. Allen and Melvin Shaw, Los Angeles, Calif.,
assignors to Hoover Products, Inc., Youngstown, Ohio,
a corporation of Ohio

Filed Dec. 11, 1959, Ser. No. 58,642

Term of patent 14 years

(Cl. D34—15)

FIG. 1

FIG. 2

FIG. 3

FIG. 4

Figure 1 is a front view of the beaded toy train showing our new design;

Figure 2 is a top plan view thereof; and

Figure 3 is a side view thereof; and

Figure 4 is a rear view thereof.

The beaded chain shown is integral and extends throughout the cars from the engine to the caboose and forms couplings therebetween.

We claim:

The ornamental design for a beaded toy train, as shown and described.
